ATTORNEYS

UNITED STATES PATENT OFFICE.

THOMAS CURRAN, OF STREATOR, ILLINOIS.

WATER-CONTROLLING DEVICE.

Application filed September 22, 1921. Serial No. 502,484.

To all whom it may concern:

Be it known that I, THOMAS CURRAN, a citizen of the United States, and a resident of Streator, in the county of La Salle and State of Illinois, have invented a new and useful Improvement in Water-Controlling Devices, of which the following is a full, clear, and exact description.

My invention relates to improvements in water controlling devices, and it consists in the combinations, constructions and arrangements herein described and claimed.

An object of my invention is to provide a water controlling device for turning on and off the flow of water in a water main and which is operated by the water pressure within the main.

A further object of my invention is to provide a water controlling device of the character described for railroad stand pipes, permitting the use of a gate valve for the control of the water, which valve provides a free way flow of water to the stand pipe.

A further object of my invention is to provide a water controlling device that is thoroughly practical for the purpose intended and not likely to get out of order easily.

Other objects and advantages will appear in the following specification, and the novel features of the invention will be particularly pointed out in the appended claims.

My invention is illustrated in the accompanying drawings, forming part of this application, in which—

Fig. 1 is a side elevation of my water controlling device,

Fig. 2 is a section of a part of the device,

Fig. 3 is a section of a part of the device along the line 3—3 of Fig. 1,

Fig. 4 is a diagrammatic view of the operating valves with the gate valve open,

Fig. 5 is a diagrammatic view of the operating valves with the gate valve closed.

In carrying out my invention, I make use of a standard gate valve 1, having an elongated spindle 2. The valve 1 is connected to a water main 3 at one of its ports and to a discharge main 4 at its other port.

Supported above the valve 1 by uprights 5 is a cylinder 6 having its ends closed by means of plates 7 and 8. The plates 7 and 8 are held in closed engagement with the cylinder 6 by the use of tie rods 9, making the cylinder water tight. Within the cylinder 6 and secured to the valve stem 2 is a piston

10. The piston 10 consists of two leather, circular members 11 fixed to two steel plates 12 which plates are securely bolted together. A rod 13 vertically disposed upon the piston 10 and in alignment with the valve stem 2 projects through the plate 7 and engages a compression spring 14. The spring 14 is normally confined between the plates 15 and 16, which plates are supported above the cylinder 6 by means of the rods 17. The rods 17 are secured to the plate 7. It will be evident that the rod 13 could be replaced by an extension of the valve stem 2, but for the sake of ease in assembly of the device, I have used the rod 13. Extending upwardly from the water main 3 is a pipe 18 provided with a valve 19. Connected with the pipe 18 are two three-way valves 20 and 21. The valves 20 and 21 are of the construction, shown in the diagrammatic Figures 4 and 5. The plates 7 and 8 are provided with vents 22 and 23 which are connected each to a port of the valves 20 and 21, respectively. A discharge pipe 24 is provided and is connected by means of two pipes 25 and 26 each to a port of the valves 20 and 21, respectively. The cylinder 6 is provided with an additional vent 27 through the plate 8, which vent is connected to a simple valve 28. The valves 20, 21 and 28 are all devised to operate at approximately a quarter of a revolution and are each provided with arms 29. The arms 29 are pivotally secured to a bar 30 which bar in turn is pivotally secured to a lever 31. The lever 31 terminates in a ring 32 which is concentric with an upright discharge pipe 33. The structure is clearly shown in Fig. 3. The lever 31 is actuated by means of a vertical rod 34, which has provided at its lower end a flattened portion 35 having two outwardly projecting fingers 36, which fingers engage the ring 32 as is shown in Fig. 1. At the opposite end of the vertical rod 34 is a bell-crank 37 which is tied by means of a rod 38 to a hand lever 39. The hand lever 39 is pivotally mounted to the spout 40 at 41. The discharge pipe 33 carrying the spout 40 is pivotally mounted to a base 42 at 43 so that it may be swung into any desired position.

From the foregoing description of the various parts of the device, the operation thereof may be readily understood. The device, as shown in Fig. 1, is shut off and the valves are in the position as indicated in Fig. 5.

When it is desired to turn on the flow of water in the spout 40, the operator moves the hand lever 39 in a downward direction. This causes the lever 31 to assume the position shown in dotted lines and in turn causes the arms 29 to move approximately 90° and assume the positions as shown in dotted lines. The valves 20, 21 and 28 are then in the position shown in Fig. 4. Water from the pipe 18 now flows down through the valve 20 and into the vent 23 at the lower part of the cylinder 6. The vent 27 at this time is closed and the valve 20 is turned so as to permit any water that may be above the piston 10 in the cylinder to pass out through the vent 22 and out of the discharge pipe 24. It will be seen, therefore, that water entering the vent 23 will cause the piston 10 to rise, carrying with it the valve stem 2 and thus open the gate valve. The spring 14 at this time is compressed.

To shut off the water, the lever 39 is moved back to the position shown in Fig. 1. The valves 20, 21 and 28 are thus moved to the position shown in Fig. 5. With the valves 20, 21 and 28 in this position, water in the cylinder 6 below the piston 10 will be discharged through the vent 23 and through the discharge port 44 of the valve 21. Water will also be discharged from below the piston 10 through the vent 27 of the valve 29, thus providing a double discharge below the piston while the gate valve is being closed. The valve 1 is closed by means of water entering the upper part of the cyl-

inder 6 through the valve 20 and by means of the spring 14 bearing down upon the rod 13, which rod is at all times in close engagement with the piston 10.

I claim:

The combination with a gate valve having a valve stem, a water main connected with the valve, and a spring for exerting a downward pressure upon said valve stem to yieldably close said valve, of a cylinder disposed adjacent to said valve, a piston within said cylinder, a rod connecting said piston with said valve stem, a valve having three ports, one port connected with said water main, another communicating with the interior of said piston at its upper end, and the third connected with a discharge pipe, a second valve having three ports, the first port being connected with said water main, the second port communicating with said cylinder at its lower end, and the third port communicating with said discharge pipe, a third valve having one port communicating with the lower end of said cylinder, and the others with a discharge pipe, and means for actuating said valves simultaneously, whereby water may enter from said main into the upper portion of said cylinders to cause said piston to move downwardly, and water within said cylinder may be discharged through the two remaining valves associated with the lower end of the cylinder to cause said gate valve to close.

THOMAS CURRAN.
